United States Patent

Des. 234,297
Patented Feb. 11, 1975

234,297

SOFT LURE BODY

James T. Peterson, 3216 Noble Ave.,
Minneapolis, Minn. 55422

Filed Apr. 5, 1973, Ser. No. 348,327

Term of patent 14 years

Int. Cl. D22—05

U.S. Cl. D22—27

FIG. 3

FIG. 1

FIG. 2

FIG. 4

FIG. 5

FIG. 1 is an end elevation view of the lure body, and the elevation view of the other end of the lure body is a mirror image of FIG. 1;

FIG. 2 is a side elevation view thereof;

FIG. 3 is a top plan view thereof;

FIG. 4 is a bottom plan view thereof;

FIG. 5 is an elevation view of the other side thereof;

I claim:

The ornamental design for a soft lure body, as shown and described.
